UNITED STATES PATENT OFFICE.

JOHN S. HANSEN, OF BROCKTON, MASSACHUSETTS, ASSIGNOR TO O. A. MILLER TREING MACHINE COMPANY, OF PORTLAND, MAINE, A CORPORATION OF MAINE.

SHOE-TREE.

1,114,349.

Specification of Letters Patent.

Patented Oct. 20, 1914.

Application filed October 29, 1909. Serial No. 525,360.

To all whom it may concern:

Be it known that I, JOHN S. HANSEN, a citizen of the United States, residing at Brockton, in the county of Plymouth and State of Massachusetts, have invented certain Improvements in Shoe-Trees, of which the following description, in connection with the accompanying drawings, is a specification, like reference characters on the drawings indicating like parts in the several figures.

This invention relates to certain improvements in shoe-trees or forms, lasts and similar devices.

One of the objects of the invention is to produce a shoe-tree or form in which the usual fore part and the heel part thereof are connected by means which permits the easy insertion of the tree in a shoe so as to snugly fit the same, or to be quickly withdrawn therefrom, combined with an improved adjusting device, so arranged and constructed as to provide for changing the length of the tree while the parts are in the shoe, or are out of the shoe, to adapt the device to shoes of different styles or sizes, as well as to, if desired, subject the shoe to a certain amount of tension in order to stretch the same.

Having in view this and other objects, the invention in its preferred form comprises a device of this character having a fore part and a heel part, a member connected with each of these parts, and a connection between such members arranged to permit relative pivotal or turning movements, and also to permit relative longitudinal or sliding movements thereof, together with a very simple, convenient, and durable form of adjusting device which I have found to be admirably adapted to the purpose of effecting the longitudinal movements of the parts of the shoe-tree. This device, in the embodiment of the invention selected for illustration herein, is composed of a suitable rotatory member, such, for example, as a nut, which is supported by and turns freely on a part joined to one of the connecting members and is in threaded engagement with a coöperating element, such, for example, as the teeth of a rack formed on, or carried by, the other of said members. Preferably, such rotatory member is in swiveled engagement with a slide which is pivotally joined to the

first-mentioned connecting member and is constrained to move longitudinally along 55 the other connecting member.

Other features of the invention will be more particularly set forth in the following description, and will be pointed out in the claims.

In the drawings, Figure 1 illustrates, in side elevation, a shoe-tree embodying my invention in position in a shoe, the shoe being shown in section and the position of the parts of the tree during its insertion and removal appearing in dotted lines; and Fig. 2 is a cross sectional view on the line 2—2, Fig. 1.

In the embodiment of the invention shown herein, the numeral 1 indicates the fore part, 70 which may be constructed of wood, or any other suitable material, in the rear portion of which is preferably formed a kerf to receive the forward end of a connecting member 3, the same being shown as pivotally 75 connected with the fore part by a suitable pin 2, though any equivalent means may be employed to movably connect said parts with each other. The member 3 is formed with a slot, 4, and is also formed, or provided, upon each of its opposite edges with a rack comprising a plurality of teeth, 5, which are so arranged as to coöperate with a worm or thread formed interiorly of a nut, 7, which surrounds and travels upon 85 the member 3 in the same manner as upon an external screw-thread, the nut having preferably an external roughened surface to enable it to be more easily turned through engagement with the operator's thumb and finger. The nut 7 is carried by a slide, 6, to which it is confined by shoulders, 8, 8, on the slide, or by other suitable means which will permit free turning movements of the nut relatively to the slide, but will prevent 95 any relative longitudinal movements of these parts.

The heel part, 14, which may be of rounded, ellipsoidal, or any other suitable form, has secured thereto the member, 10, which is 100 provided with an extension having an angular portion, 13, to constitute a handle for the convenient insertion of the tree into a shoe or for its removal therefrom, as well as for properly manipulating the toggle members, 105 3, and 10. At its forward end the member

10 is pivotally connected with the slide 6 by a pin, 11, which also passes through the slot 4.

By this construction it will be seen that the members 3 and 10 are pivotally joined together and that the member 3 is pivoted to the fore part so as to turn relatively thereto, whereby, if the parts of the tree are in the position shown by dotted lines in the drawing and are inserted in a shoe, and downward pressure applied to the connecting members through the handle, said members will act in the manner of a toggle to separate the fore and heel parts of the tree and to seat them firmly and snugly against the inside of corresponding parts of the shoe. If adjustments of the tree are desired, the operator may apply his thumb and a finger to the nut 7, and by turning it in one direction will cause the nut to travel along the teeth 5 rearwardly to separate the parts of the tree and thereby increase its length, and by turning the nut in the opposite direction will cause it to travel along the teeth in the proper direction to contract said parts and thereby decrease the length of the tree. These adjustments may be accomplished very easily, and with the hand which inserts the tree in, or removes it from a shoe, either prior to or after the tree has been inserted in position. In the latter case, the threaded connection between the nut 7 and the member 3 is such as to provide a powerful leverage which enables the operator, through said parts, to exert the desired amount of stretching pressure against the fore part and heel part of the shoe.

It is to be understood that the invention is not limited to the details of construction herein shown and described, but such details may be varied and the invention may be embodied in other forms, without departing from the principles thereof.

Having thus described my invention,

what I claim as new and desire to secure by 45 Letters Patent of the United States, is:—

1. A shoe-tree having, in combination, a fore part, a heel part, a member connected with one of the said parts and provided with a rack, a member connected with the other of said parts, a slide pivoted to the last-named member and a rotary device carried by said slide and constructed and arranged to engage the teeth of said rack, to effect longitudinal adjustments of the shoe-tree. 55

2. A shoe-tree comprising a fore part, a heel part, a toggle member pivotally connected with one of said parts and having its edges provided with teeth, a toggle member connected with the other of said parts, a slide pivoted to the last-named member and arranged for longitudinal movements relatively to the first-named member, and a nut encircling the slide and toothed member and rotatively mounted on said slide 65 whereby it is adapted to coöperate with said teeth in effecting relative adjustments of the fore and heel parts.

3. A shoe-tree comprising a fore part, a heel part, a toggle member connected with 70 one of said parts, said member having a slot and also having its edges provided with teeth, a toggle member connected with the other of said parts, a slide, means passing through the slot in the first-named toggle 75 member and pivotally connecting said slide and last-named toggle member, and a rotary device carried by said slide and adapted to coöperate with said teeth in effecting relative adjustments of the fore and heel parts. 80

In testimony whereof I have signed my name to this specification in the presence of two subscribing witnesses.

JOHN S. HANSEN.
